The ornamental design for a drone, as shown and described.

DESCRIPTION

FIG. 1 is a bottom perspective view of a drone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top perspective view thereof.

The dashed broken lines in the drawings represent portions of the drone that form no part of the claimed design.
